UNITED STATES PATENT OFFICE.

CARL REISS, OF BERLIN, GERMANY.

INVERTED LAMP.

No. 806,428.

Specification of Letters Patent.

Patented Dec. 5, 1905.

Application filed February 2, 1905. Serial No. 243,885.

To all whom it may concern:

Be it known that I, CARL REISS, a subject of the King of Prussia, German Emperor, and a resident of 16^a Oberwallstrasse, Berlin, 5 Kingdom of Prussia, German Empire, have invented certain new and useful Improvements in Inverted Lamps, of which the following is an exact specification.

My invention relates to improvements in inverted lamps, and more especially to such arrangements in which the mixing tube or tubes are surrounded by a receptacle open at the upper end. In the hitherto-known arrangements such receptacles had the purpose 15 to keep away the burnt gases from the mixing-tubes and to effect a circulation of air downwardly from above.

The main feature of my arrangement consists therein that the receptacle reaches above 20 the mixing-tubes and is provided at its lower end with air-inlet openings, so that an air-current permanently passes from below through the interior of the receptacle, thereby cooling the mixing tube or tubes and preventing too strong a heating of the latter. 25 Fresh air is continuously drawn in into the interior of the receptacle and then flows upward.

In the accompanying drawings, Figures 1 30 and 2 show two side views of my invention. Fig. 3 is a longitudinal section, and Fig. 4 is a section on line A B. Figs. 5 and 6 show different forms of the receptacle used in my lamp. Figs. 7 and 8 show two further constructional forms of my invention.

In Figs. 1 to 4, *a* is a receptacle surrounding the mixing-tubes of the burners *d*, which latter lead air-tight through the bottom *e* of the receptacle *a*, which receptacle is open at the 40 top. *b* represents partition-channels provided at the receptacle *a* for leading away separately the combustion-gases. *c* is a gas-conduit for feeding the burners. *f* represents exit-openings arranged in the upper part of 45 the passages *b*. *g* represents openings in the lower part of receptacle *a*, through which enters the fresh air. The upper end of the receptacle *a* is closed by a cover *h*, provided with openings *i*, through which the air leaves.

50 The operation is as follows: The fresh air enters the openings *g*, feeds the mixing-tubes of the burners *d*, whereas the remaining air is heated in the receptacle *a* and leaves through the openings *i*, thereby permanently sucking in a sufficient quantity of air and cooling the

mixing-tubes and the gas-conduit *c*. The gases of combustion enter from the surrounding globe *o* and leave the exit-passages *b* through the openings *f*. Figs. 5 and 6 show a hexagonal and octagonal receptacle *a*, thereby enabling a putting in of a larger number of burners or mixing-tubes within the receptacle *a*, *b* being again the partition-channels for the gases of combustion.

In the arrangement according to Fig. 7 65 tubes *k* are provided extending through the partition-channels *b*, opening outwardly, of the extent of the combustion-gases and connecting the outside to the interior of the receptacle *a*. *f* represents again exit-openings 70 for the combustion-gases.

Fig. 8 shows a further convenient form, the burners and mixing-tubes being not shown. *m* represents the exit-openings for the gases of combustion, arranged at the bottom *e* of the receptacle *a*, caps *n* being provided laterally to these openings *m* for deflecting the combustion-gases. *l* is one of the openings at the side of the caps *n* and admitting fresh air to the receptacle *a*. In all cases the inlet-openings for the fresh air are so laterally arranged with regard to the exit-openings of the combustion-gases as to prevent the latter to enter the receptacle *a*.

Having thus fully described the nature of my invention, what I desire to secure by Letters Patent of the United States is—

1. In a lamp, an inverted gas-burner, a gas and air mixing device, a receptacle protecting the said mixing device against the combustion-gases having openings near its lower end and openings at its upper end serving as air inlet and outlet for producing an upward air circulation through the heating 90 of the receptacle by hot combustion-gas, and channels adjacent to the receptacle for leading away the combustion-gas substantially as described.

2. In a lamp, an inverted gas-burner, a gas and air mixing device, a receptacle protecting the said mixing device against the combustion-gases having openings near its lower end and openings at its upper end serving as air inlet and outlet for producing an upward air circulation through the heating 95 of the receptacle by hot combustion-gas, channels adjacent to the receptacle for leading away the combustion-gas, and air-tubes connecting the lower openings of the recep- 100 105 110

tacle through the said channels outward of the extent of the hot combustion-gas with the atmosphere, substantially as described.

3. In a lamp, an inverted gas-burner, a gas and air mixing device, a receptacle protecting the said mixing device against the combustion-gases having openings near its lower end and openings at its upper end serving as air inlet and outlet for producing an upward air circulation through the heating of the receptacle by hot combustion-gas, a bottom plate at that receptacle with open-

ings between said receptacle and the globe of the lamp for leading away the hot combustion-gas, and deflecting-caps protecting the lower opening of the receptacle against the arising combustion-gas, substantially as described.

In witness whereof I have hereunto set my hand in the presence of two witnesses.

CARL REISS.
